The ornamental design for a battery cover for hand held apparatus such as an optical scanner, as shown and described.

DESCRIPTION

FIG. 1 is a top front perspective view of a first embodiment of a battery cover for hand held apparatus such as an optical scanner showing our new design;

FIG. 2 is a top rear perspective view of the first embodiment; FIG. 3 is a bottom front perspective view of the first embodiment;

FIG. 4 is a bottom rear perspective view of the first embodiment;

FIG. 5 is a front elevation view of the first embodiment; FIG. 6 is a rear elevation view of the first embodiment;

FIG. 7 is a right side elevation view of the first embodiment; FIG. 8 is a left side elevation view of the first embodiment;

FIG. 9 is a top plan view of the first embodiment; FIG. 10 is a bottom plan view of the first embodiment;

The broken line showing in FIGS. 1-10 is included for the

purpose of illustrating environmental structure only and

forms no part of the first embodiment.

FIG. 11 is a top front perspective view of a second embodiment of a battery cover for hand held apparatus such as an optical scanner showing our new design;

FIG. 12 is a top rear perspective view of the second embodiment;

FIG. 13 is a front elevation view of the second embodiment; and,

FIG. 14 is a top plan view of the second embodiment.

The broken line showing in FIGS. 11-14 is included for the purpose of illustrating environmental structure only and
